UNITED STATES PATENT OFFICE.

MICHAEL JOHN GRADY AND RICHARD MCMILLAN, OF KINGSTON, CANADA.

CAR-COUPING.

SPECIFICATION forming part of Letters Patent No. 537,527, dated April 16, 1895.

Application filed November 30, 1894. Serial No. 530,319. (No model.)

To all whom it may concern:

Be it known that we, MICHAEL JOHN GRADY and RICHARD MCMILLAN, of the city of Kingston, in the Province of Ontario, in the Dominion of Canada, have invented certain new and useful Improvements in Car-Couplings; and we do hereby declare that the following is a full, clear, and exact description of the same, reference being had to the accompanying drawings, in which—

Figure 1, is a horizontal section of a pair of drawheads coupled, embodying our invention. Fig. 2, is a like view of one of the drawheads uncoupled. Fig. 3, is a like view of the other drawhead, adjusted for coupling. Fig. 4, is a section on line X X Fig. 2. Fig. 5, is a section on line Y Y, Fig. 3, and Fig. 6, is a perspective view of the locking block or keeper, detached.

Our invention relates to that class of drawheads which have a knuckle hinged to the front to interlock with a like knuckle on the other drawhead, and our invention has for its object to effect self coupling of the knuckles by displacement of a keeper or locking block which drops from a recess in the cavity of the drawhead into engagement with one arm of the knuckle to couple, and uncoupling is effected by lifting the keeper by a lever to 30 turn it into the recess.

Our invention consists in the construction, arrangement and combination of parts of the drawhead, or coupling, as hereinafter described and claimed.

A, is the body of the drawhead having arms a, a', at the front which receive intermediately the opposite coupling.

B, is a V-shaped knuckle hinged to arm a, by a pintle b, passing through the elbow and 40 through jaws on the arm, so that when the inner arm b², of one knuckle is pushed by the outer arm of the opposite knuckle, both knuckles embrace one another as shown in Fig. 1, to effect coupling. The lower end of the knuckle is provided with a projection b³, shown in dotted lines, which enters a corresponding notch in its bearing, to temporarily hold the knuckle adjusted to couple when forced out by the opposite coupling or by a 50 spring hereinafter referred to as shown in Fig. 3. The knuckles are kept embraced or coupled and uncoupling effected by the fol-

lowing described means which constitute our invention.

The drawhead has an internal cavity d, in front and the top of one side is extended horizontally to make a shelf or recess d', to lodge the locking block or keeper when uncoupled.

D, is a V-shaped keeper or locking block in the cavity d, and in thickness less than half the height of the cavity. When coupling is effected said keeper rests on the bottom of the cavity, and in the recess d', when uncoupled.

E, is a pin passing through the top and bottom of the cavity, and loosely through the elbow of the keeper, and said pin projects below the bottom of the drawhead to guide the rising and falling motions of the keeper in coupling and uncoupling.

F, is a sleeve or pipe inclosing a portion of the pin E, and the keeper D, bears on the top of said sleeve, and the lower end of the sleeve bears on one arm of an elbow lever G, which at the elbow is pintled to a lug a⁴, on the under side of the drawhead, and said arm is provided with a slot through which the pin passes to allow movement, and the pin is provided with a stop pin e, to limit the descent of the arm.

The lever is operated by a pull rod K, which extends to the side of the car, and is provided with a notch or stop L, to engage a fixed staple or guide M, to keep the lever at the position shown in Fig. 5, when coupling is not desired. When rod K, is pulled, lever G, lifts sleeve F, and raises keeper D, level with the recess d'.

The pull on the knuckle of the opposite drawhead then rocks knuckle B, and causes its arm b², to push one arm of the keeper D, so that it will lodge in the recess d', and thereby permit the embracing knuckles to separate to uncouple. The lodgment of the keeper in the recess prevents it from falling to the bottom of the cavity after the pull rod has been released, and in the raised position the keeper is ready for coupling. Coupling is effected by the locking arm b², of the interlocking knuckle striking the curved arm of the keeper D, and swings the keeper so that the end or arm resting in the recess d', will be shifted out, and the keeper drop by gravitation when the meeting walls of sides of keeper and cavity are parallel, as shown

in Fig. 2, so that the keeper will engage the arm b^2 , of the knuckle and prevent it rocking, and thereby lock the knuckle of the opposite drawhead when both knuckles embrace.

5 If desired, the sleeve or pipe F, may be integral with the keeper D.

N, is a notch in the outer arm of the knuckle B, to receive the link of another coupling, and O, is the pin-hole to hold the link in the 10 notch.

C, is a spiral spring having one end fixed into the knuckle B, at the heel, and the other end frictionally engaging the wall of cavity d, of the drawhead, so that when the knuckle 15 is released to uncouple, the spring will swing the knuckle outwardly to the position to couple automatically.

We claim as our invention—

1. The combination with the drawhead having arms a, a', cavity d, and recess d', of the V-shaped knuckle B, hinged to said arm a, and having an arm b^2 , entering said cavity, the pin E, passing vertically through said cavity, the V-shaped locking block or keeper 20

25 D, sleeved on said pin to gravitate and lock said arm b^2 , to effect coupling, as set forth.

2. The combination with the drawhead A,

having arms a, a', cavity d, and recess d', of the V-shaped knuckle B, hinged to said arm a, a spring C, swinging said knuckle outwardly when released, a pin E, passing vertically through said cavity, a V-shaped locking block D, sliding on said pin to gravitate and engage the arm b^2 , of the knuckle, and a lever 30 G, lifting said locking block and relieving the 35 knuckle when said block is partly swung into the recess d', to uncouple, as set forth.

3. The combination with the drawhead having an internal cavity d, and a recess d', therefrom horizontally near the top, the V-shaped 40 knuckle B, hinged to the front of the drawhead and having an arm b^2 , entering said cavity, of the pin E, passing through said cavity, and extending below the drawhead, the keeper D, sleeved on said pin to gravitate, the lever G, lifting said keeper, and the pull rod K, extending below the drawhead and operating the lever, substantially as set forth. 45
